UNITED STATES PATENT OFFICE.

JOHANNES RUTHS, OF DJURSHOLM, SWEDEN, ASSIGNOR TO AKTIEBOLAGET VAPOR-ACKUMULATOR, OF STOCKHOLM, SWEDEN, A CORPORATION OF SWEDEN.

STEAM PLANT.

Application filed January 8, 1923, Serial No. 611,535, and in Sweden January 13, 1922.

My invention relates to accumulation of heat in steam plants having a demand for hot water and more particularly to the automatic preparation and accumulation of hot water to normally obtain a constant pressure of hot water prepared, for the purpose of obtaining constant temperature, while steam generation is effected independently of demand for steam or hot water and complete equalization in the plant is obtained.

My invention involves a new type of automatic controlled accumulator and a new method of operation of steam plants.

The invention is illustrated on the accompanying drawing of which:—

Fig. 1 shows an accumulator equipped to carry out the present invention; and Fig. 2 shows a modified accumulator arrangement.

In Fig. 1, reference character *a* designates a container operating as an accumulator, preferably made as an upright cylindrical vessel. Steam is supplied through pipe *c* which constitutes a source of variable steam supply and the steam flows out through nozzles *d* into the water space of the container *a*. Container *a* is closed to the atmosphere.

Cold water is supplied to container *a* through the pipe *e* and through spray-nozzle *g*. Flow through pipe *e* is controlled by valve *f*. Valve *f* is controlled by means of a regulator *h* which is responsive to static pressure within container *a*. Pressure in container *a* acts through tube *r* against piston *s* which is connected to valve *f*. A rise of pressure in container *a* causes valve *f* to increase its flow area, thereby increasing flow of cold water through pipe *e* whereas, upon decrease of the pressure actuating valve *f*, the same is operated to decrease the flow of water through pipe *e*. Valve *f* is set to open at a predetermined value of pressure depending upon the temperature of water desired. When the pressure rises above this predetermined value the valve opens; when the pressure falls below this value the valve closes.

Consumers are supplied with hot water through conduit *k*. The supply of hot water to the consumers may be in accordance with demand for hot water and entirely independent of the amount of steam passing through pipe *c*.

If desired steam may be withdrawn from container *a* through pipe *l*.

The operation is as follows:

Assume that the accumulator is to deliver water of a constant temperature of a given number of degrees and that the water level for the moment corresponds to that designated by reference character *m*. Steam, ordinarily the surplus generated steam of the plant, flows into pipe *c* from any place of steam supply in regular or irregular quantities according to plant characteristics. The steam flows into container *a* heating the water contents thereof, as a result of which the pressure rises. Rise of pressure in container *a* causes an opening or increase of opening of valve *f* and cold water flows through pipe *e* and through spray-nozzle *g* into the container so that steam in the upper part of the container *a* is condensed and the pressure and consequently the temperature fall to obtain a return to equilibrium.

If the steam supply decreases, the pressure in the steam space falls somewhat as a result of which valve *f* closes somewhat and reduces the supply of cold water so that water of a given temperature is again obtained. Thus the regulating valve *f* operates in response to static pressure in container *a* to admit at all times a sufficient amount of water corresponding to the amount of steam supply to maintain a constant pressure and temperature of accumulated water.

When steam is extracted through pipe *l* the temperature will fall momentarily. Normally however the above regulation gives a constant temperature control.

Fig. 2 shows an arrangement wherein container *a* is a small receptacle which supplies prepared hot water through conduit *k*² to an accumulator tank *a*¹. The operation of this arrangement is the same as that of Fig. 1 except that the variation of water level corresponding to the state of charge of the accumulator takes place in the larger tank *a*¹ and not in container *a*.

In plants where the present invention can be applied, it has the advantage over the valve pressure type of accumulator in that the complete heat content of the accumulator is fully utilized.

In the warm water accumulator of the present application, the water level *m* is a

function of the state of charge of the accumulator. When the accumulator is discharged, the water level sinks. When the accumulator is fully discharged, it contains little or no water. When the accumulator is again charged, the water level rises. While the water level varies continuously, the pressure and temperature within the accumulator remain constant. The height of

10 water level is indicated by a gage *b*.

While I have described some forms of my invention, it is to be understood that this is merely by way of example and that

15 the invention is not limited to the embodiments disclosed.

What I claim as new and desire to secure by Letters Patent of the United States is:—

20 1. Accumulator apparatus for steam plants comprising a container, means to supply steam to said container, means to supply cold water to said container and means movable in response to changes of static pressure in the container to control the cold water supply.

25 2. Accumulator apparatus for steam plants comprising a container closed to the atmosphere, means to supply steam to said container, means to supply cold water to said container and means responsive to changes of static pressure of steam in said container to control the cold water supply.

30 3. Accumulator apparatus for steam plants comprising a container, means to supply steam to said container, means to supply cold water to said container and automatic pressure responsive means to control the cold water supply and operating to maintain a constant pressure in said container.

35 4. Accumulator apparatus for steam plants comprising a container, means to supply a varying quantity of steam to said container, means to mix cold water with said steam and pressure responsive means to maintain a constant temperature of the mixture.

40 5. Accumulator apparatus for steam plants comprising a container, a steam pipe conducting steam to said container, a cold water supply pipe conducting cold water to said container, a valve in said cold water supply pipe, a regulator responsive to pressure in said container to operate said valve by increasing the flow of cold water through said cold water supply pipe upon an increase of pressure in said container, and decreasing the said flow upon decrease of pressure in said container.

45 6. Steam accumulator apparatus for steam plants comprising a container having a steam space and a water space, a conduit leading steam into the water space, a water conduit leading water into the steam space.

50 65 a spray device attached to the last mentioned conduit, a valve in said water con-

duit, means responsive to the pressure in said container to operate said valve, said means operating to open the valve when the pressure in said container rises above a predetermined value and means to conduct hot water from said container.

7. Those steps in the operation of a steam plant which consist in conducting surplus steam to an accumulator, supplying cold water to the accumulator and regulating the cold water supply in accordance with variations of static pressure in the accumulator.

8. In a steam plant, in combination, a constant pressure, variable water level accumulator containing water at different heights for different times, means to supply steam to said accumulator, means to supply cold water to said accumulator to condense said steam and produce hot water, said accumulator being constructed and arranged to store the hot water produced until there is a demand for the hot water, and means responsive to pressure in the accumulator to control the supply of cold water and operating to normally maintain a constant pressure in the accumulator.

9. In a steam plant, in combination, a constant pressure, variable water level accumulator closed to the atmosphere and containing water at different heights for different times, a steam charging device in the water space of the accumulator, means to supply steam to said steam charging device, means to supply cold water to said accumulator to condense said steam and produce hot water, said accumulator being constructed and arranged to store the hot water produced until there is a demand for the hot water and means responsive to pressure in the accumulator to control the supply of cold water and operating to normally maintain a constant pressure in the accumulator.

10. In a steam plant, in combination, an accumulator, means to supply surplus steam generated over momentary steam demand to said accumulator, pressure controlled means to supply cold water to said accumulator in proportion to the steam supplied to obtain hot water of given pressure, means to withdraw hot water from said accumulator at a rate corresponding to the rate of demand for hot water, the difference between the hot water demand and the hot water produced being retained in the accumulator.

11. In a steam plant, in combination, a source of variable steam supply, a constant pressure variable water level accumulator, means to conduct steam from said source to said accumulator, means to supply cold water to said accumulator, automatic means to control the cold water supply in response to pressure in said accumulator and means to withdraw hot water from said accumulator.

12. The method of generating and dis-

compensating energy in a steam plant which comprises generating steam at a rate different than the rate of steam demand, condensing surplus steam by means of cold water to such an extent as to obtain hot water in the presence of steam, regulating the supply of cold water so that the hot water produced by the mixing of steam and cold water is maintained at constant pressure, accumulating hot water thus produced and using the hot water as desired.

13. In a steam plant, an accumulator comprising a container closed to the atmosphere, and having a water space and a steam space, means to supply steam to said accumulator, means to supply cold water to said accumulator to condense said steam and produce hot water, said accumulator being constructed and arranged to store the hot water produced until there is a demand for hot water, means to withdraw hot water from said accumulator, means to withdraw steam from said accumulator, and pressure responsive

means to control the supply of cold water to maintain a constant pressure in the accumulator except when steam is withdrawn. 25

14. In a steam plant, an accumulator having a water space and a steam space, means to supply steam to said accumulator, means to supply cold water to said accumulator to condense said steam and produce hot water, said accumulator being constructed and arranged to store the hot water produced until there is a demand for hot water, means to withdraw hot water from said accumulator, 30 means to withdraw steam from said accumulator and pressure responsive means for controlling the supply of cold water to maintain a constant pressure in the accumulator when steam is not withdrawn, to shut off the cold water supply when steam is withdrawn and the pressure drops, and to admit cold water when the pressure rises again and a given value of pressure is reached. 35

In testimony whereof I affix my signature.
JOHANNES RUTHS.
